UNITED STATES PATENT OFFICE

JOHN O. WAGNER, OF CHICAGO, ILLINOIS

SCREEN CONSTRUCTION

Application filed November 21, 1927. Serial No. 234,661.

This invention relates to a screen construction for swinging ventilators and concerns itself primarily with the construction between the screens and ventilator.

5 The difficulty heretofore encountered in screened ventilator construction existed in the fact that the contacting parts between the ventilator and screens would not always provide a tight fit when the ventilator was 10 open. In certain of the prior art devices, arcuate contact rolls have been provided between the ventilator and screens. On account of variations in width between the ventilator and screens such contact rolls 15 would not always provide a good fit. Moreover the same were always more or less costly. In other devices of the prior art, the contact plate on the ventilator moves the upper screen both outwardly and upwardly. 20 This naturally requires the upper screen to be loosely mounted, a thing which is objectionable. Sometimes this upward movement becomes too great for the space afforded whereby the particular structure becomes impracticable for certain places. 25

It is an object of this invention to overcome these objectionable features of prior devices in the provision of simple contact members between the ventilator and screens, which 30 contact members can be cheaply produced, which can be readily adjusted for variations in space and which will also produce a good fit between the ventilator and screens when the former is open.

35 The invention comprises the novel structure and combinations hereinafter described and more particularly pointed out and defined in the appended claims.

In the accompanying drawings, which illustrate certain preferred embodiments of this invention and in which similar reference numerals refer to similar features in the different views:

40 Figure 1 is a fragmentary elevational view of a window embodying this invention.

Figure 2 is an enlarged sectional view taken substantially upon the line II-II of Figure 1.

45 Figure 3 is an enlarged sectional view taken upon the line III-III of Figure 1,

showing the ventilator in open position in dotted lines.

Figure 4 is an enlarged fragmentary sectional view taken upon the line IV-IV of Figure 1.

55 Figure 5 is an enlarged fragmentary sectional view taken upon the line V-V of Figure 1.

Figure 6 is an enlarged fragmentary sectional view taken upon the line VI-VI of Figure 4.

60 Figure 7 is an enlarged fragmentary sectional view illustrating a modified contact member and showing in dotted lines the window in tilted position.

65 Figure 8 is an enlarged fragmentary sectional view of the window with parts omitted and showing an adjustable contact member.

In referring to the drawings, especially 70 the Figure 1, it will be noted that I have illustrated a pivoted or swingable ventilating section 2 in connection with a window 1, though the same may be a wall or the like.

The frame of the ventilating section comprises an upper angle member 3, a similar 75

lower angle member 4 and side stiles 5, with suitable intermediate framing for supporting the panes. It will be noted that the vertical flanges of the angle members 3 and 4 abut the adjacent frame members 6 and that the

80 horizontal flange of the member 4 abuts an angle member 8 secured to the adjacent frame member 6. This particular construction allows the ventilating section to pivot in only

85 one direction. Welded to the side members 5 of the ventilating section and swingable therewith are channel shaped members 9, (Figure 4), for bridging the gap between

such side member 5 and the adjacent frame member 6 of the window. A leaf spring 9a is secured to the stationary frame member 6 and extends between the members 5 and 6 and bears against the channel member 9 for closing the channel when the ventilator is

90 open to prevent insects from entering.

95 Upon the front side of the ventilator section 2, there is a contact member 10 which is secured at its ends to the side members 5 of the ventilating section. Contact member 10 comprises a flat vertical portion 10a and an 100

upper portion 10^b which slopes toward and contacts with the glass and frame. Upon the rear side of the ventilating section, there is another contact member 11 comprising a flat vertical portion 11^a, and an upper portion 11^b which slopes toward and contacts the glass and ventilator frame. The flanges 10^b and 11^b of the contact members, on account of their slopes may be readily bent 5 upwardly or downwardly in the field for varying the respective distances between the ventilator and the contact members according to the space afforded by different structures or locations, and according to the thickness of the glass of the ventilator.

Upon the upper frame member 6, there are a pair of clips 12, (Figure 2). The function of these clips 12 is to confine the upper frame member 13 of the upper screen. Upon the 20 stationary side rail 6 adjacent the ventilating opening, are suitable angle clips 14, to which angular seats 15 are secured, as shown in Figure 4, for receiving the side frame member 13^a of the screen. Suitable guide bolts 16 extend 25 from the sides 13^a of the upper screen and through suitable slots 17 in the side seats 15, whereby the upper screen is capable of a limited vertical movement.

The lower frame member 18 of the upper window screen is normally positioned against the contact member 10, as shown in Figure 3, while the upper frame member 13 of such screen is confined between the clip 12 and against the depending portion of the de- 30 formed portion 7, as shown in Figure 2. The lower screen has an upper frame member 19 which is normally retained against the guard member 11 by securement to a bracket 28 on the frame members 6, (Figure 3). The lower frame member 20 of the lower screen is supported upon suitable angle clips 21 secured to an angle member 22 upon adjacent frame member 6 as shown in Figure 5.

The contact member 10 may be made in a 43 substantial arcuate form comprising a plurality of sections at slight inclinations to each other, as indicated by the members 10^c of Figure 7 whereby the ventilator will always have a close fit between the screens when open. Instead of sloping the flanges of the contact members, they may be made of two parts as shown in Figure 8 in which the depending portion 23 is adjustably connected to the upper portion 24 by a bolt 25 carried by the member 23 and extending through a slot in the member 24. The depending portion 23 can then be laterally adjusted for variations in thickness of glass or ventilator space.

Normally the parts comprising the upper 60 and lower screen and the intermediate ventilating section occupy the relative positions as shown in Figure 3. The ventilating section is pivoted by the lugs 26 on the side members 5 to suitable lugs or brackets 27 on the adjacent side frame members 6, and is adapted

to swing as shown in dotted lines in Figure 7. During such swinging movements, the upper screen will be slid upwardly, as is evident from a comparison of Figures 3 and 7. It will be noted that a rolling action arises between the screen frame and the ventilator, and the ventilator will swing a considerable distance before moving the upper screen. It should, however, be noted that the ventilator 2, in its open position, effectively closes 75 the space between the screens, as shown in Figure 7.

I am aware that many changes may be made, and numerous details of construction may be varied through a wide range without departing from the principles of this invention, and I therefore do not purpose limiting the patent granted thereon, otherwise than necessitated by the prior art.

I claim as my invention:

1. In a window construction comprising a swingable ventilating section having a side member with an adjacent window frame member spaced from said side member, a channel shaped member secured to said side member and resilient means secured between said frame member and said channel shaped member.

2. In a window construction comprising spaced frame members, with a swingable ventilating section between said frame members, a channel shaped member having unequal flanges secured to one side of said section, said flanges overlapping parts of the adjacent frame member, and a leaf spring secured to said adjacent frame member and positioned in said channel shaped member.

In testimony whereof I have hereunto subscribed my name.

JOHN O. WAGNER.
